BOX OR SIMILAR ARTICLE

Arthur R. Botham, New York, N. Y., assignor to J. R. Wood & Sons, Inc., New York, N. Y., a corporation of New York

Application December 29, 1951, Serial No. 17,873

Term of patent 14 years

(Cl. D80—5)

To all whom it may concern:

Be it known that I, Arthur R. Botham, a citizen of the United States, residing at 45 East 50th Street, city of New York 22, State of New York, have invented a new, original, and ornamental Design for a Box or Similar Article, of which the following is a specification, reference being had to the accompanying drawing, forming a part hereof.

Fig. 1 is a top plan view of a box showing my new design; and

Fig. 2 is a front elevation.

The dominant features of my design reside in the portions shown in full lines.

I claim:

The ornamental design for a box or similar article, substantially as shown and described.

ARTHUR R. BOTHAM.
